US00D987585S

(12) **United States Design Patent** (10) **Patent No.:** **US D987,585 S**
(45) **Date of Patent:** **** May 30, 2023**

(54) **CROSS BAR FOR POWDER COATING AND ELECTRONIC COATING**

(71) Applicant: **Production Plus Corp.**, Ashville, OH (US)

(72) Inventor: **Donovan Dixon**, South Bloomfield, OH (US)

(73) Assignee: **Production Plus Corp.**, Ashville, OH (US)

(**) Term: **15 Years**

(21) Appl. No.: **29/776,264**

(22) Filed: **Mar. 29, 2021**

Related U.S. Application Data

(63) Continuation of application No. 16/734,003, filed on Jan. 3, 2020, now Pat. No. 10,960,418.

(57) **CLAIM**

The ornamental design for a cross bar for powder coating and electronic coating, as shown and described.

DESCRIPTION

FIG. 1 is a front perspective view of a cross bar for powder coating and electronic coating;

FIG. 2 is a front elevation view thereof;

FIG. 3 is a rear elevation view thereof;

FIG. 4 is a right-side plan view thereof;

FIG. 5 is a left-side plan view thereof;

FIG. 6 is a top view thereof;

FIG. 7 is a bottom view thereof; and,

FIG. 8 is a rear perspective view thereof.

The brackets and break lines in the drawing views indicate that the appearance of any portion of the article between the break lines forms no part of the claimed design.

1 Claim, 4 Drawing Sheets
